UNITED STATES PATENT OFFICE.

JOSEPH THIEM, OF NEWPORT, KENTUCKY.

TRAIN-PIPE COUPLING.

1,156,191.

Specification of Letters Patent.

Patented Oct. 12, 1915.

Application filed June 23, 1915. Serial No. 35,767.

To all whom it may concern:

Be it known that I, JOSEPH THIEM, a citizen of the United States, and a resident of Newport, in the county of Campbell and 5 State of Kentucky, have invented certain new and useful Improvements in Train-Pipe Couplings, of which the following is a specification.

My invention relates to pipe couplings; 10 and its object is to provide for automatic coupling of the train pipes when the cars are coupled together, relieving the trainman of the necessity of going under the cars to make the connections between the pipes, 15 and also to provide for automatic uncoupling of these pipes when the cars are uncoupled.

My invention consists in the combination 20 of parts and in the details of construction and arrangement of parts as will herein be mere fully described and claimed.

In the drawings: Figure 1 is a front elevation of a device embodying my invention, showing one of the coupling heads, and showing 25 the position in which it is mounted on the end of a car, this coupling being provided for a single pipe line; Fig. 2 is a similar view of the modification in which the coupling is provided for three pipe lines; Fig. 3 is a plan view of the coupling for a single pipe line, both heads being shown coupled together, and showing one of the cocks for cutting out the coupling; Fig. 4 is a detail plan view of one 30 of the single coupling heads; Fig. 5 is a side view of the device as shown in Fig. 3; and Fig. 6 is a detail plan view of one of the triple coupling heads.

The coupling heads 1 are mated and inversely presented on two cars to be coupled, 40 and located substantially under the couplers 2 of the cars. Each head has a rearwardly extending elongated neck 3 guided in a U-shaped hanger 4 fixed on the under side of the car frame, and this neck 3 and the head 45 have a longitudinal passage 5 through them which, at the rear end of the neck 3, receives a pipe 6 which projects into the train pipe 7, with a stuffing box 8 around it on the end of the train pipe, thereby permitting 50 sliding of the pipe 6 along with the head 1, while the train pipe 7 is stationarily mounted on the frame of the car as usual. The cut-out cock 7^a is interposed in the 55 train pipe 7 adjacent to the pipe 6, and operated by means of a rod 7^b. The U-shaped hanger 4 is of sufficient vertical extent to

allow the head with its neck 3 to slide up and down therein to allow for the relative up and down motion of the two different cars having the coupling heads coupled together. 60 Between the rear ends of the neck 3 and the stuffing boxes 8 are helical springs 9 which hold the coupling heads outward, these coupling heads being normally projected out past the couplers 2 of the cars, and when 65 the cars are brought together and coupled, each coupling head is pressed back against its spring 9 and the resistance of the spring causes the coupling heads to be tightly 70 pressed together.

Around the outer terminal or mouth of the passage 5 in each coupling head is a gasket 10 made up of two flanges 11 and 12, joined by a central part 13 of lesser diameter, one of the flanges 11 being received in 75 an annular groove 14 around the passage 5 slightly backward from the mouth. The other flange 12 lies outside the mouth, and these flanges 12 of the gaskets on the respective coupling heads are pressed tightly 80 together when the device is coupled, thus making a continuous communication from one coupling head to the other, and therefore from one train pipe 7 to the other on the two cars.

To assist in holding the coupling heads together by steadyng their engagement, each one of them is provided on one side with a wide flat prong 15 vertically disposed, and on its other side with a slot 16 vertically disposed in such a manner that it receives the prong 15 of the other coupling head, which, as hereinbefore stated, is inversely presented. Outside the slot 16, there is a recess 17 in which is swung on vertical pivots 18 a jaw 19, the rear end 20 of which may swing into the slot 16, while the front end swings outward from in front of the slot. The inner side of this front end has a vertically disposed elongated lug 21. The rear outer corner 22 at the other side of the coupling head is made square, and this corner 22 on each coupling head is adapted to fit behind the lug 21 of the jaw 19 of the other coupling head, being held thereagainst by the engagement of the rear end of the prong 15 with the rear end 20 of the jaw 19, which prong enters through the slot 16 and pushes the rear end of the jaw 19 outward. While the lug 21 thus hooks around the opposite coupling head its projection is slight enough 100 so that it will readily be pulled loose when 105 110

the prong disengages from the rear end 20 of the jaw 19 as the cars are separated. The necks 3 of the coupling head may have lugs 23 to the rear of the hangers 4 to limit 5 the forward movement of the coupling heads when the car is separated and cause this pulling apart of the coupling heads.

To compensate for the slight up and down motion that may occur between the coupled 10 heads, I prefer to make the mouths of the passages 5 somewhat higher than they are wide, as shown in Figs. 1 and 2, and the gaskets 10 will be shaped accordingly.

As is well known, passenger trains are 15 provided with three pipe lines, one for the air brakes, one for the heating system and one for the signal system. Accordingly, I may provide coupling heads 1' each with three passages 5^a, 5^b and 5^c as shown in Figs. 20 2 and 6. The necks 3' of these coupling heads will be widened to accommodate the increased number of passages, as will also 25 the hangers as indicated by the hanger 4' in Fig. 2. It will be understood that the three lines of pipes enter the respective passages, and each will be provided with a pipe 6 entering the respective pipe on the car corresponding to the pipe 7 and provided with 30 a stuffing box 8. However, it will not be necessary to provide a spring 9 on each pipe, since merely the middle pipe or merely the 35 two side pipes may have such springs to equalize the yielding support of the coupling head forwardly. The other parts of the triple coupling will be the same as those 40 described in connection with the examples of Figs. 1, 3, 4 and 5. The coöperating prongs 15 and jaws 19 will so bind the coupling heads together and equalize the pressure across them that all of the gaskets 10 will make tight contact and render the 45 respective pairs of pipes on the two cars continuous.

Having fully described my invention, what 45 I claim as new and desire to secure by Letters Patent is:

1. In a train-pipe coupling, in combination with train pipes, inversely disposed mated coupling heads, air-tight connecting 50 means clamped between them, each coupling head having a pipe extending rearwardly therefrom, which pipes communicate through said coupling heads brought together as aforesaid, each of said pipes extending into a respective train pipe, and a stuffing box on each train pipe around the one of said pipes extending thereinto.

2. In a train-pipe coupling, in combination with train pipes, inversely disposed 55 mated coupling heads, air-tight connecting means clamped between them, each coupling head having a pipe extending rearwardly therefrom, which pipes communicate through said coupling heads brought together as aforesaid, each of said pipes ex-

tending into a respective train pipe, and a stuffing box on each train pipe around the one of said pipes extending thereinto, and a spring interposed between each of said coupling heads and the respective stuffing box. 70

3. In a train-pipe coupling, in combination with train pipes, inversely disposed mated coupling heads, air tight connecting means between said heads, a rearwardly extending neck on each coupling head, a hanger flanking said neck and secured to a railway vehicle centrally thereof under the coupling thereof, each coupling head and its neck having a passage therethrough, a pipe fixed in the rear end of each neck and communicating with the respective passage, movable connection between each of said pipes and a respective train pipe, and a spring interposed between each neck and the respective train pipe around the pipe 85 that is fixed to the neck.

4. In a train-pipe coupling, in combination with train pipes, inversely disposed mated coupling heads, air-tight connecting means between said heads, a rearwardly extending neck on each coupling head, a hanger flanking said neck and secured to a railway vehicle centrally thereof under the coupling thereof, each coupling head and its neck having a passage therethrough, a pipe fixed in the rear end of each neck and communicating with the respective passage, each of said pipes extending into a respective train pipe, and a stuffing box on each train pipe around the respective pipe extending thereinto. 95

5. In a train-pipe coupling, in combination with train pipes, inversely disposed mated coupling heads, air-tight connecting means between said heads, a rearwardly extending neck on each coupling head, a hanger flanking said neck and secured to a railway vehicle centrally thereof under the coupling thereof, each coupling head and its neck having a passage therethrough, a pipe fixed in the rear end of each neck and communicating with the respective passage, each of said pipes extending into a respective train pipe, a stuffing box on each train pipe around the respective pipe extending thereinto, and a helical spring around each of said pipes between the neck and the stuffing box. 105

6. In a train-pipe coupling, in combination with train pipes, inversely disposed mated coupling heads, air-tight connecting means clamped between them, a jaw pivoted on each one of said coupling heads, with a front end adapted to engage behind the other coupling head, and a rear end to be engaged to cause this engagement of the front end with the other coupling head, and means on each coupling head to engage with the rear end of the jaw on the other coupling head to cause said engagement of the 110 115 120 125 130

front end when the coupling heads are brought together.

7. In a train-pipe coupling, in combination with train pipes, inversely disposed mated coupling heads, air-tight connecting means clamped between them, a jaw pivoted on each one of said coupling heads, an inwardly extending lug on the front end of each jaw to engage with an adjacent corner 10 of the other coupling head when the front end of the jaw is swung inward, said jaw having a rear end to be engaged inwardly, and a prong on each coupling head to engage with said rear end of the jaw on the 15 other coupling head to swing said jaw as aforesaid.

8. In a train-pipe coupling, in combination with train pipes, inversely disposed mated coupling heads, air-tight connecting 20 means clamped between them, each of said coupling heads having a prong and a slot disposed oppositely to each other, the prong of each coupling head being received into the slot of the other coupling head when 25 they are coupled together, and a jaw pivoted on each one of said coupling heads adjacent to the slot thereof, with a rear end engaged by the prong of the other coupling head when it is received into the slot of the 30 respective coupling head, and thereby being swung outward and swinging the front end of the jaw inward, and an inwardly extending lug on the front end of each jaw to engage with an adjacent corner of the other 35 coupling head when the front end of the jaw is thus swung inward.

9. In a train-pipe coupling, in combination with train pipes, inversely disposed mated coupling heads, air-tight connecting 40 means clamped between them, each of said coupling heads having at one side a prong and at the other side a slot, the prong of each coupling head being received into the slot of the other coupling head when they 45 are coupled together, each of said coupling heads having a recess extending inwardly from the adjacent side into its slot, and a jaw pivoted in each one of said recesses to swing on a vertical axis, with a rear end 50 swinging into said slot to be engaged by the prong of the other coupling head, and an inwardly extending lug on the front end of the jaw to engage with an adjacent corner of the other coupling head when the front 55 end of the jaw is swung inward by the engagement of the prong of the other coupling head, with the rear end of this jaw thus swinging outward.

10. In a train-pipe coupling, in combination 60 with train pipes, inversely disposed mated coupling heads, air-tight connecting means clamped between them, each of said coupling heads having a passage through it and having an annular slot around the passage a short distance inward from its mouth,

a gasket for each coupling head comprising rear and forward flanges joined by a middle part of lesser diameter, the rear flange entering said annular groove and the forward flange lying outside of the mouth of the passage to engage with the forward flange of the other coupling head, each of said coupling heads having a recess extending inwardly from the adjacent side into its slot, and a jaw pivoted in each one of said recesses to swing on a vertical axis, with a rear end swinging into said slot to be engaged by the prong of the other coupling head, and an inwardly extending lug on the front end of the jaw to engage with an adjacent corner 70 of the other coupling head when the front end of the jaw is swung inward by the engagement of the prong of the other coupling head, with the rear end of this jaw thus swinging outward. 75

11. In a train pipe coupling, in combination with train pipes, inversely disposed mated coupling heads, air-tight connecting means clamped between them, a rearwardly extending neck on each coupling head, a hanger flanking said neck and secured to a railway vehicle centrally thereof under the coupling thereof, each coupling head and its neck having a passage therethrough, a pipe 80 fixed in the rear end of each neck and communicating with the respective passage, 85

movable connection between each of said pipes and a respective train pipe, and a spring interposed between each neck and the respective train pipe around the pipe that is 90 fixed to the neck. 95

12. In a train-pipe coupling, in combination with train pipes, inversely disposed mated coupling heads, air-tight connecting 100 means clamped between them, a rearwardly extending neck on each coupling head, a hanger flanking said neck and secured to a railway vehicle centrally thereof under the coupling thereof, each coupling head and its neck having a passage therethrough, a pipe 105 fixed in the rear end of each neck and communicating with the respective passage, each of said pipes extending into a respective train pipe, and a stuffing box on each train pipe around the respective pipe extending 110 thereto. 115

13. In a train-pipe coupling, in combination with train-pipes, inversely disposed mated coupling heads, air-tight connecting means clamped between them, a rearwardly 120 extending neck on each coupling head, a hanger flanking said neck and secured to a railway vehicle centrally thereof under the coupling thereof, each coupling head and its neck having a passage therethrough, a pipe 125 fixed in the rear end of each neck and communicating with the respective passage, each of said pipes extending into a respective train pipe, a stuffing box on each train pipe around the respective pipe extending there- 130

4
into, and a helical spring around each of said pipes between the neck and the stuffing box.

14. In a train-pipe coupling, in combination with train pipes, inversely disposed mated coupling heads, air-tight connecting means clamped between them, each coupling head having a pipe extending rearwardly therefrom, which pipes communicate through said coupling heads brought together as aforesaid, each of said pipes extending into

a respective train pipe, and a stuffing box on each train pipe around the one of said pipes extending thereinto, a cut-out cock interposed in each of said train pipes past the 15 end of the pipe extending into the train pipe, and an operating rod for said cut-out cock.

JOSEPH THIEM.
